COMBINED CAP AND DISPENSER FOR JARS
AND THE LIKESamuel A. de Waltoff, Los Angeles, Calif., assignor
to Deleit Enterprises, Inc., Los Angeles County,
Calif., a corporation of California

Application September 5, 1945, Serial No. 614,553

2 Claims. (Cl. 222—390)

1

My invention relates to an interchangeable combined cap and dispenser for jars and the like, adapted to be attachable to an empty jar having viscous contents therein, particularly to cosmetic cold cream jars having an inner tapering wall portion.

One of the important objects of my invention is in the embodiment of a double cap arrangement, in which the outer plastic member is provided with an inner metallic threaded member that is secured to the top open portion of the jar, after which the outer plastic member may be rotated as desired, to force downwardly a pusher or disk piston member and its paper-like washer contacting the viscous contents within the jar, for expelling same through a hollow screw stem member onto the top of the outer plastic cap. Single cap members made of plastics generally are affected by changes of temperatures, in which they may crack or split open when secured tightly to the jar, hence the use of an inner metal cap member secured within a rotatable outer plastic cap member.

Another object of my invention is the advantage of my inner metal member, that is adapted to be secured to any type of jar having locking means, because of the low cost of changing the inner cap member to correspond to the particular locking means of any jar as plastic caps would require expensive moulds to make plastic caps to fit onto different types of jars, and therefore, it is believed that my inner low cost metal cap would be more preferable.

A further object of my invention is that a single cap arrangement may be adopted as a much preferred form, in which event, this cap would be of plastic or metal, and the tubular stem and the piston member and its paper-like washer, are operated by a knob-like portion fully rotatable on or in the crown portion of the cap secured to the jar.

For further understanding of my cap attachment unit, it is applied to the outside of a container or jar having within suitable viscous contents, such as cold cream for example, having affixed to it the usual cover, which is removed and discarded, and in place thereof, the inner metal cap member of my double cap attachment unit is then secured to the jar which has a downward tapering bore. Now, by simply turning the outer rotatable cap member associated with my unit, the cold cream will be expelled through an inner tube normally sealed by a cap-stopper. Such expressing is achieved by having a threaded tubular stem member secured as an integral part

2

of the outer or top cap member. The threaded tubular stem member carries a pusher member onto which is placed a paper washer having a yieldable periphery rim portion, so when the latter contacts the inner tapered wall portion of the jar during rotation of the top cap and extended threaded stem which forces the pusher member and paper washer onto the cold cream, the periphery rim portion of the paper washer is also forced down into the increasingly constricted bore of the jar, and a wiping contact is obtained onto the inner face of the tapered wall portion. In other words, the periphery rim edge of the paper washer will yield under pressure thereby curling or be compressed onto the tapered wall portion, so that all of the cold cream within the jar will be projected and expelled upwardly through the tubular threaded stem member to a desired height above a mound portion of the outer cap member, whereat it is readily scooped off by the fingers of the user, and when jar becomes empty the paper washer will remain in its wedged position at the bottom of the empty jar, and then the combined cap and depressing device is reattached to another full jar of cold cream, previous to which a clean and newly fresh paper-like washer has been attached to the underside of the disk portion of the pusher member, the previous used paper-washer being wedged into the extreme bottom portion of the discarded jar.

Other objects of this invention will appear as the description proceeds in the following specification, accompanied by the annexed drawings in which

Figure 1 is an exterior elevational view of the interchangeable combined cap and dispenser device of my invention.

Figure 2 are exploded sectional views of the attaching device shown in Figure 1 together with the jar.

Figure 3 is a sectional view of the attachment unit or device shown in Figure 2, attached to a jar for dispensing the cold cream or similar viscous contents therefrom.

Figure 4 are exploded sectional views of all of the component parts forming the attaching device, namely, the discharge plastic mound cap member, the combined outer rotatable cap, the hollow screw stem member, the inner metallic cap member, the pusher member and the yieldable saucer-like paper-like washer member, and under liquid-proof layer, shown in dot and dash lines.

Figure 4a shows an elevational view of a smooth bottom disk pusher member.

Figure 5 is a sectional view showing the inner cap member substituted by a metal threaded ferrule member within the outer rotatable cap member.

Figure 6 is a sectional view showing a single plastic cap with a rotatable screw-member and rotatable knob extending through the crown portion of the fixed cap member.

Figure 7 is a bottom plan view of the agitator member as used in the extreme bottom end of the hollow screw-stem member shown in Figure 6.

Figure 7a is a modification of the agitator shown in Figure 7.

Figure 8 is an enlarged fragmentary sectional view of the periphery portion of the plastic cap member shown in Figure 6.

Figure 9 is a plan view of the yieldable paper washer member shown of this invention.

Figure 10 is a sectional view of the cap unit similar to Figures 2 and 3, in which a gasket-like piston ring is used in place of the yieldable rim-portion of the paper-like washer.

Figure 10a shows in section a pusher member formed by die stamping.

Figure 11 is an exterior elevational view of the attachment device when applied to a cream jar, or the like, similar to that shown in Figure 3.

Figure 12 is a view in perspective illustrating the attaching operation of the cap attachment of this invention to a cream jar, or the like.

Referring to the drawings, an outer plastic cap member 1 is provided with a top crown portion 2 that may or may not have a boss or mound portion 3 having a counterbore portion 4 into which is fitted tightly a threaded screw-like stem or tubular member 5 provided with a hollow passage 6, all of which are made of any suitable plastic, metallic, transparent or translucent material. The tubular member 5 with its stem portion may be formed integral with the outer cap member 1, but is considered not practical.

Under the outer or upper plastic cap member 1 is another or second cap member 7, preferably made of metal, which has a central opening 8 adapted to be snapped into a circular groove portion 9 of an inner boss portion 10 of the outer cap member 1, thereby forming a combined double cap arrangement. The inner boss portion 10 may or may not be provided with a recessed or counterbored portion 11 to receive the collar-boss portion 12 of a pusher or piston pressure disk member 13 having pointed projections 13a on the bottom thereof, onto which is mounted and secured a flexible or yielding washer-like ring member 14, for example, made of paper, which may be treated with chemicals to make same liquid proof, or may be untreated, in which event, thin waxed paper washers 14a may be added to prevent the cream soaking into the paper-like washer 14.

It is to be noted that the periphery edge portion 15 is crimped or formed at 16, see Figures 4 and 9, to allow same to yield in the downward movement in the constricted bore and against the inner tapering wall portion IW of a jar J, which may have reduced top rim portion, onto which is secured the inner metal cap member 7 by screw-like threads, projections or as otherwise desired, after the cover C, shown in dot-dash lines in Figure 2, has been removed.

In the illustrative view of Figure 2, it is obvious that when my cap attachment unit AU is being attached to the jar J, the viscous contents VC within the jar, will enter the hollow passage 6 of the screw-like stem member 5, in which the

viscous contents may rise until it contacts the washer 14, whereby the friction therewith will prevent the washer and pusher member from turning when the outer plastic cap member is slightly turned which rotates the screw-like stem member 5, thereby forcing the pusher member 13 and washer 14 downwardly against the viscous contents VC, which is forced upwardly through the passage 6 and outwardly onto the mound 3, clearly shown in Figure 3.

In event the viscous contents VC within the jar does not fill the jar completely, thereby leaving a space under the washer 14 when in its uppermost and normal position as shown in Figure 10, means may be adopted to move the pusher member 13 down until it contacts the viscous contents VC, such as for example, by a projecting tab or lug 16, on the pusher member 13.

When the cap attachment unit AU is not in use onto jar J, a sealing cap 20 is placed onto the top boss or mound portion 3 which is slightly tapered, (or may be screw-threaded, if so desired) and a plug-like or stopper portion 21 seals the mouth opening 3 of the discharge passage 6 within the screw stem 5.

The cap attachment unit AU when attached and secured firmly to the reduced open end portion M of the jar J, provides a seal therat, thereby providing three distinct sealing means for the jar and the cap attachment unit, the other two sealing means being the yielding periphery rim portion of the washer-disk member 13 under forced pressure onto the inner tapering wall portion IW of the jar, and the discharge opening cap member 20 with its plug or stopper portion 21 into the cream discharge opening 3 of the cap attachment unit AU.

In Figure 5, an inner metal ferrule screw member 25 may be used in place of the inner metal cap member 7, which also allows the outer cap member 1 to freely rotate, similar to the arrangement shown in Figure 3, and by the beaded rim portion BR of the cap 7.

In Figure 6, a single cap member 1a of any desired material is shown with a threaded rim TH and a reduced mound portion 3a, onto which is secured a knob 3b of the extended member similar to the threaded stem portion 5 of Figure 5, which is locked and secured for example, by a lock washer of split halves secured in the counterbore portion of the cap member 1a or by a key pin 5c.

An agitator 27 may be or may not be attachable to and removable from the end portion of the hollow screw-stem 5, thereby preventing clogging or jamming of the cream in the entrance space ES, see Figure 3, and assist in keeping this space passable for the forced cream or viscous contents therethrough. However, other means may be adopted, just so it is as effective for the same purpose. The washer 14 may or may not be cut as at 21a to allow same to fit onto agitating member 27, as the agitator must operate in rotation beneath the washer 14 which is held stationary against cream under pressure by the disk pusher member 13, which is held stationary simultaneously by the pointed projections

13a, or any other suitable means as may be desired, or the underside of the disk 13 may be perfectly smooth as shown in Figure 4a, or may have a fine or rough finish to grip washer. The paper-like washer 14 may not contact the full underside portion of the pusher member 13, may

fit like a ring in the shoulder portion 13c and 13d as shown in Figures 10 and 10a.

In Figure 10 a gasket-ring or resilient piston-ring member 30, or this may be the paper-like washer 13 formed in a ring member, either of which may be fitted into the depressed portion 31 of the pusher member 13a, which may be a stamping 13b, such as shown in Figure 10a, the collar portion 12" being threaded to suit.

In Figure 11 an exterior view shows the cap 10 attachment unit AU secured to the jar J when not in use, and Figure 3 shows same in use, with the forced cream projecting above the mound portion 3, whereat the cream is scooped off by the fingers of the user.

In Figure 12 an illustrative view in perspective, clearly shows the cap attachment unit AU being attached to a full jar of cold cream, in which the hollow portion 6 of the screw stem 5 may be thoroughly cleaned as shown, or may still retain cold cream from its previous cold cream jar to which it was attached.

The inner cap member 7 may have a corrugated rim portion 45c, which may be all around as shown, or partially spaced, so in securing the cap to a new full jar, the thin rim portion of the outer cap member 1 may be squeezed until it contacts the corrugated portions 45c, thereby turning threaded rim of the inner cap member 7 for securing same to the jar J, the cap 7 may or may not be provided with corrugated portions 45d, in full depth or a part thereof.

It is to be understood that similar parts in different views in drawings may have the same numeral primed, and the double threaded tubular stem portion 5 may have standard V-shape threads, and any of the parts hereinbefore described, may be as otherwise desired, and I do not wish to confine myself to the exactness of any part or detail shown in the drawing, and reserve the right to alter and improve same, providing same comes within the scope of the appended claims.

It is to be further understood that the double threaded stem portion 5 in which the square type of threaded and long pitch of threads, enables the user to rotate the free outer cap slightly, and also provides a neat and safe construction, is easily handled and is safe in washing and cleaning operations, in which V-pointed threads may cut the fingers or hands. However, the V-pointed threads can be chamfered and smoothed sufficiently to make them safe also. The pitch of the threads is a matter of adoption, but it is believed that much time is saved by the double threads, whereby a slight turn is all that is necessary, especially among theatrical, stage or movie, actors and actresses, this saving of time is of importance.

What I claim as new and desire to secure by

Letters Patent of the United States of America, is as follows:

1. A combined cap and dispensing attachment device for jars and the like, and of the character described, comprising an upper cap member provided with a recessed crown portion having a counter-bored portion, a threaded hollow stem member extending therefrom, said recessed crown portion having a hole therethrough, whereat it communicates with the hollow portion of said stem member, a boss portion provided with a circular groove portion, a second cap member provided with a similar recessed crown central opening and a flange rim portion, said central opening of said second cap member secured rotatably in said circular groove of said boss portion of said outer cap member, a disk-like pusher member having a threaded collar-boss portion arranged and operative on said threaded hollow stem member, said disk-like pusher member normally positioned within the inner recessed crown portion of said second cap member, with said collar-boss portion extending in said counterbored portion, whereby the flange rim portion of said second cap member is adapted to be attached to a jar having viscous contents therein.
2. A combined cap and dispensing attachment device for jars and the like, and as defined in claim 1, said outer cap member provided with a downwardly lug projection, said disk-like pusher member provided with a upwardly lug projection, when outer cap member is rotated said lug projections are engaged thereby propelling said disk-like pusher member until it contacts said viscous contents, whereat said lug projections become disengaged, whereby said disk-like pusher member is then propelled by said outer cap member and its co-acting threaded hollow stem member.
